ADJUSTABLE HEAD BAND DEVICE

Donald E. Kimball, Cleveland, Ohio, assignor to
Eausch & Lomb Optical Company, Rochester,
N. Y., a corporation of New York

Application May 6, 1938, Serial No. 206,434

11 Claims.

(Cl. 2—14)

This invention relates to an adjustable head band for eye protectors, and the like, and has for an object the provision of new and improved head bands of this character. The present application forms a continuation in part of my co-pending application, Serial Number 143,307, filed May 18, 1937.

In the drawings accompanying this specification and forming a part of this application, I have shown, for purposes of illustration, embodiments which my invention may assume, and in the drawings:

Figure 1 is a top plan view of goggles, to which opposite ends of the adjustable head band are connected, the intermediate portion of the band being broken away to better accommodate the view to the sheet.

Figure 2 is a side elevational view of one of the goggle cups, showing a fragment of the head band connected thereto.

Figure 3 is an enlarged, longitudinal vertical sectional view through the head band, the view being intermediately broken, and only fragments of the attaching means being shown, this view disclosing one embodiment of the adjustable connection between the head band and the eye protectors.

Figure 4 is an enlarged end elevational view, partially in section, and corresponding substantially to the line 4—4 of Figure 3.

Figure 5 is a transverse sectional view corresponding substantially to the line 5—5 of Figure 3.

Figure 6 is an end elevational view of a different embodiment of the connecting means for the head band.

Figure 7 is a fragmentary longitudinal, vertical, sectional view of said embodiment, corresponding substantially to the line 7—7 of Figure 6, and showing the parts in one position.

Figure 8 is a sectional view similar to Figure 7, and showing the parts in a different position.

Figure 9 is a transverse sectional view, corresponding substantially to the line 9—9 of Figure 8.

Figure 10 is a front elevational view of still another embodiment of the adjustable fastening means, and showing the parts in one position.

Figure 11 is a longitudinal vertical sectional view corresponding substantially to the line 11—11 of Figure 10.

Figure 12 is a transverse sectional view corresponding substantially to the line 12—12 of Figure 11.

Figure 13 is a view similar to Figure 12 cor-

responding substantially to the line 13—13 of Figure 11, while

Figure 14 is a view similar to Figure 10, showing the parts in a different position.

As shown in Figures 1 through 5 of the drawings, this embodiment of the invention comprises a pair of eye cups 15 and 16, each contoured, as at 17, to fit the face of the user, the cups being connected by a flexible adjustable nose piece 18, of any well known type, while the outer rear edge of each of the eye cups 15 and 16 has fixedly secured thereto, by any suitable means, a bracket 19, provided with a slot 20 for the reception of the curled end 21 of a hinged part 22. Each hinged part 22 is split, and bent, as at 23, to fixedly accommodate an end ball of a chain 24, made up of a plurality of balls 25, flexibly connected by connecting bars 26, each of the chains 24 being relatively short, and preferably consisting of five or six balls 25, and a sufficient number of inter-connecting bars 26.

Cooperating with the chains 24—24, and completing the head band, is a head band portion 27 which comprises a coiled spring 28, the end portion 29 of which is fixedly held in a crimped groove 30, formed in a cup-shaped thimble or ferrule 31, the forward wall 32 of which is provided with a centrally disposed circular aperture 33, while the end portion 29 of the coiled spring 28 has a dimetrically disposed terminal end portion 34, which extends across one side of the circular aperture 33, and provides a catch for engagement between pairs of balls 25, being resiliently yieldable to permit passage of balls therewith by application of considerable force thereto, for purposes of adjustment. The opposite end of the coiled spring 28 is provided with an oppositely disposed ferrule arrangement identical to that already described and similar reference characters will be employed to designate like parts of the two constructions. Each of the ferrules 31 is provided with an annular skirt portion 35, and surrounding the spring 28 and extending within the skirt 35 of the ferrule, is a fabric sheath 36, each end of which is provided with extensions 37 projecting through slots 38 formed in the skirt 35, these extensions being turned back and held in place by a flexible ring 39 tightly fitted thereover, both ends of the sheath thereby being fixedly connected to the ferrules 31. The sheath is of greater length than the unextended length of the coiled spring 28, and of sufficient length so that the spring may stretch a predetermined limited distance, dependent upon the length of the sheath, the

20

25

30

35

40

45

50

55

sheath being puckered somewhat along the spring 28 when the latter is unextended. In this way the spring may be stretched to accommodate this portion of the head band to the head of the user, yet stretching of the spring is limited by the length of the sheath 36.

Adjustment of the overall length of the head band, including the portion 27 and the chains 24—24, may be effected by moving one or more balls 25 inwardly or outwardly with respect to the adjacent ferrules 31, the catch 34 permitting this operation when considerable force is applied in effecting the adjustment, but maintaining the adjustment once it is made.

15 Referring to Figures 6 through 9 a somewhat different embodiment of the head band portion 27 is disclosed, the chains 24, and the remainder of the construction being as heretofore described. In this embodiment the head band portion 40 20 comprises a coiled spring 41, the intermediate portion of which has the individual coils inclined in the usual way and disposed relatively close together, as at 42, while each end portion of the spring is formed to provide a vertically disposed 25 coiled section 43, substantially at right angles to the long axis of the coil, and outwardly disposed relatively widely spaced sections 44, the sections 43 and 44 extending within a cup-shaped thimble or ferrule 45, and held in position by transversely extending pins 46, engaging in the rear of the coiled section 43, thereby causing the coiled sections 44 to bear toward the front wall 47 of the ferrule or thimble 45. The front wall 47 of the thimble 45 is provided with a central 30 circular aperture 48 of a size to admit the balls 25 of the chain 24, and interposed between the end section 44 and the inner surface of the thimble wall 47, is a disk 49, notched as at 50, for the reception of a rib 51 formed in the thimble 45, the disk 49 having a circular aperture 52 normally disposed out of line with the aperture 48, as best shown in Figures 8 and 9, so that once a ball 25 has reached a position in the rear of the disk 49, it cannot be withdrawn, unless 40 the disk is tilted about its notched end, as shown in Figure 7, to line up the apertures 48 and 52, this tilting movement taking place against the pressure exerted by the coil sections 44, which normally retain the disk 49 in the position shown 45 in Figure 8. An aperture 53 is formed in the wall 47, through which an implement, such as a nail, or the like, may be inserted to tilt the disk 49, to line up the apertures 48 and 52, and enable the balls to be adjusted with respect to the 50 thimble 45. The opposite end of the coiled spring 41 will be provided with an adjusting arrangement identical to that already described, but not shown, as will be understood. Surrounding the spring 41 is a sheath 54, similar to the sheath 36. In this instance, however, each end of the sheath 54 fits over the exterior wall of the thimble 45, and held in place by a ring 55, which is secured in position by the pins 46, the sheath being of greater length than the spring 41 in its 55 normal unextended position, and sufficiently long to permit predetermined extension of the spring, but limiting this extension, as before explained.

Another embodiment of the head band portion is disclosed in Figures 10 through 14, this embodiment including a coiled spring 60, the coil sections of the intermediate portion of which are normally disposed relatively close together, and at each end the coiled spring 60 is formed with a 70 coil section 61, extending substantially at right

angles to the axis of the spring, and outwardly of the section 61 the spring is provided with several relatively widely spaced coil sections 62. Clamped onto the section 61, by means of ears 63, is a sheet-metal sleeve 64, which fits within a cup-shaped thimble 65 and is held in position by transversely extending pins 66. The forward wall 67 of the thimble 65 is provided with an off-center circular aperture 68, large enough for reception of the balls 25 of the related chain 24, and interposed between the inner surface of the wall 67 and the end coil section 62 of the spring, is a disk 69 having an off-center aperture 70, opening into curved slot 71, the aperture 70 in one position, as shown in Figure 14, being adapted to register with the aperture 68 to permit free insertion and removal of the balls 25, and in another position after rotation, as shown in Figure 13, to be out of line with the aperture 68, so that the link 26 of the chain 25 may enter 20 into the curved slot 71. The disk 69 may be rotated by inserting an implement, as a nail, or the like, into the curved slot 72 formed in the wall 67 of the thimble, and into an opening 73 formed in the disk 69 in line with the slot 72. 25 Tits 74 may be formed upon the inner surface of the wall 67 and the outer surface of the disk 69 so that the disk may be substantially locked in position to prevent retraction of the balls 25. The opposite end of the spring 60 is provided 30 with a similar arrangement, as will be understood. A sheath 75, similar to the sheaths 36 and 54 already described, surrounds the spring 60, fits over the thimble 65, and is held in position by a band 76, affixed to the thimble by the pins 66, the sheath being somewhat longer than the spring 60 in its unextended position, and adapted to limit extension of the spring as before described.

In all of the described constructions a head 40 band is provided which is extremely light, which may be readily adjusted for size, which is elastic after adjustment, and in which there is a limit of elastic extension, all making for quick accurate adjustment and comfortable application 45 to the head of the wearer.

It will be apparent to those skilled in the art that I have accomplished at least the principal object of my invention, and it also will be apparent to those skilled in the art that the embodiments herein described may be variously changed and modified, without departing from the spirit of the invention, and that the invention is capable of uses and has advantages not herein specifically described; hence it will be appreciated that the herein disclosed embodiments are illustrative only, and that my invention is not limited thereto.

I claim:

1. Head band means, comprising: an elongated section, having hollow defining means, bounding an interior space, normally unextended, but elastically stretchable; a sheath surrounding said defining means, and connected thereto, said sheath being extensible a limited extent less than said defining means, and operable to limit stretching of said defining means; an elongated non-stretchable section; and means, constructed and arranged to connect said sections only at their adjacent end portions.

2. Head band means, comprising: an elongated section, having hollow defining means, bounding an interior space, normally unextended, but elastically stretchable, said defining means being in the form of a coiled spring; a sheath enclosing 75

5 said defining means, and connected thereto, said sheath being extensible a limited extent less than said defining means, and operable to limit stretching of said defining means; an elongated non-stretchable section; and means, constructed and arranged to connect said sections only at their adjacent end portions.

10 3. Head band means, comprising: a plurality of elongated sections arranged end to end, one of said sections having a plurality of spaced enlargements, and an adjacent section having means defining an aperture for the selective reception of said enlargements; means for adjustably securing said enlargements against retraction from said aperture; an article to which said head band means are adapted to be connected; and means for connecting the free ends of said sections to said article.

15 4. Head band means, comprising: a plurality of elongated sections arranged end to end; and means constructed and arranged to form an adjustable connection between said sections, one of said sections having a plurality of spaced enlargements, and another section including a wall portion having an aperture, and a second wall portion having an aperture, said wall portions being relatively movable to align or disalign said apertures to permit passage of said enlargements therewith when in alignment, and to restrain passage thereof when disaligned.

20 5. Head band means, comprising: a plurality of elongated sections arranged end to end; and means constructed and arranged to form an adjustable connection between said sections, one of said sections having a plurality of spaced enlargements, and another section including a wall portion having an aperture, and a second wall portion having an aperture, one of said wall portions being relatively rotatable with respect to the other to align or disalign said apertures to permit passage of said enlargements therewith when in alignment, and to restrain passage thereof when disaligned.

25 6. Head band means, comprising: a plurality of elongated sections arranged end to end; and means constructed and arranged to form an adjustable connection between said sections, one of said sections having a plurality of spaced enlargements, and another section including a wall portion having an aperture, and a second wall portion having an aperture, one of said wall portions being shiftable broadside with reference to the other to align or disalign said apertures to permit passage of said enlargements therewith when in alignment, and to restrain passage thereof when disaligned.

30 7. Head band means, comprising: a plurality of elongated sections arranged end to end; means constructed and arranged to form an adjustable connection between said sections, one of said sections having a plurality of spaced enlargements, and another section including a wall portion having an aperture, and a second wall portion having an aperture, said wall portions being relatively movable to align or disalign said apertures to permit passage of said enlargements therewith when in alignment, and to restrain passage thereof when disaligned; and means for yieldably holding said wall portions against relative movement.

35 8. Head band means, comprising: a plurality of elongated sections arranged end to end, one of said sections having hollow defining means, bounding an interior space, normally unextended, but stretchable, and an adjacent non-stretchable section, and connecting means constructed and arranged to form an adjustable connection between said sections, one of said sections having a plurality of spaced enlargements, and another section including a wall portion having an aperture, for the selective reception of said enlargements, said connecting means including a device for securing said enlargements against retraction from said aperture.

40 9. Head band means, comprising: a plurality of elongated sections arranged end to end, one of said sections having hollow defining means, bounding an interior space, normally unextended, but stretchable, and an adjacent section being nonstretchable; and means constructed and arranged to form an adjustable connection between said sections, said second mentioned section having a plurality of spaced enlargements, and said first mentioned section including a wall portion having an aperture, and a second wall portion having an aperture, said wall portions being relatively movable to align or disalign said apertures to permit passage of said enlargements therewith when in alignment, and to restrain passage thereof when disaligned; said defining means being constructed and arranged to yieldably bear upon said wall portions to prevent relative movement therebetween.

45 10. Head band means, comprising: a plurality of elongated sections arranged end to end, one of said sections having hollow defining means, bounding an interior space, normally unextended, but stretchable, and an adjacent non-stretchable section, connecting means constructed and arranged to form an adjustable connection between said sections, one of said sections having a plurality of spaced enlargements, and another section including a wall portion having an aperture, for the selective reception of said enlargements, said connecting means including a device for securing said enlargements against retraction from said aperture, and cover means cooperating with said hollow defining means and enclosing the same, said cover means being extensible, but to a less extent than said defining means; and operable to limit stretching of said defining means.

50 11. Head band means, comprising: a plurality of elongated sections arranged end to end; means constructed and arranged to form an adjustable connection between said sections, one of said sections having a plurality of spaced enlargements, and another section including a wall portion having an aperture, and a second wall portion having an aperture, said wall portions being relatively movable to align or disalign said apertures to permit passage of said enlargements therewith when in alignment, and to restrain passage thereof when disaligned; means for yieldably holding said wall portions against relative movement; an article to which said head band means are adapted to be connected; and means for connecting the free ends of said sections to said article.
